Attorney

UNITED STATES PATENT OFFICE.

JOHN F. BECK, OF GRAND RAPIDS, MICHIGAN.

FLUE-CALKING MACHINE.

1,206,080.

Specification of Letters Patent. Patented Nov. 28, 1916.

Application filed March 25, 1916. Serial No. 86,813.

To all whom it may concern:

Be it known that I, JOHN F. BECK, a citizen of the United States, residing at Grand Rapids, in the county of Kent and State of Michigan, have invented certain new and useful Improvements in Flue-Calking Machines, of which the following is a specification.

My invention relates to improvements in appliances for holding and guiding calking tools when calking the ends of boiler tubes in locomotive boilers, and its objects are: first, to provide a means whereby the calking tool may be held in the exact necessary position to form a perfect bead at the end of the tube when forming it over against the surface of a boiler front; second, to provide an implement of the kind named that may be adjusted to meet different conditions in the boiler tube, and, third, to provide an implement of the kind named which will render it impossible to throw the point of the calking tool in position to cut into and mar the surface of the boiler front, or to cut and crumble the edge of the end of the tube when forming it into a bead and forcing it into such close contact with the surface of the boiler front to form, therewith, a steam tight joint. I attain these objects by the mechanism illustrated in the accompanying drawing, in which—

Figure 1 is a sectional elevation of a boiler front and tube with my device, also in section, shown in its relative position with the calking tool; Fig. 2 is a like view of the boiler front and tube with my device in place showing how the calking tool is applied therewith, and Fig. 3 is an end view of the body part of my implement with the handle removed, showing the openings for the reception of the calking tool.

Similar numerals refer to similar parts in each of the several views shown.

In Figs. 1 and 2 I have shown a transverse vertical sectional view of the boiler front —1—, and a longitudinal sectional view of a boiler tube —2— in which my implement is to be used. 3 represents the body, 4, represents the shank, and 5 represents the head of an ordinary calking tool for forming the bead 14 on the ends of boiler tubes —2— after they have been offset in the holes in the front 1 preparatory to forming the bead. When this tool is held in position for forming the aforesaid beads without any guiding implement but the hand

of the operator it is almost impossible not to carry it out of proper position, at some point or points in the circle of the tube, to such an extent as to endanger the marring of the boiler front or disfiguring the bead being turned at the end of the tube. To obviate this difficulty without making a special calking tool, I provide a metal guide consisting of a body 6, made of a size to pass closely but freely into the ends of the tubes, and a flange 17 of sufficient diameter and thickness to allow of forming an annular groove of sufficient size and form to exactly fit over the bead when it is fully formed. This body and flange have a slot or mortise 18 made in it of sufficient size and dimensions to easily receive the head 5 of the calking tool. This slot, while of the exact width of the thickness of the head 5 of the tool, is considerably deeper than the transverse thickness of the head of the tool so a supporting plate 12 may be inserted back of the tool and held in adjustable position by means of proper springs, as 13, 13 of sufficient strength to hold the tool in exact proper position, and in firm contact with the surface of the tube, as indicated in Fig. 1. The offset or ledge 15 is designed to prevent the end of the supporting plate 12 from being forced out of the slot 18 at the back end of the body of my implement. The other end of the supporting plate 12 is adjustably held in position by means of a slotted arm 9, fitted into the receptacle 9' in the stem 8, and held therein by means of a retaining pin 10, as shown in Fig. 1 and indicated in Fig. 2.

The handle 7 is adjustably secured upon the stem 8 by means of a retaining pin 11, passed through the stem and a slot, 16, in each side of the handle so the handle may be adjusted, not only pivotally, but may also be slid laterally on said stem so it may be made available for use with any ordinary calking tool.

It will be readily understood that when power is applied to the shank 4 of the calking tool the action of the springs 13, 13 and the adjustable handle 7 will cause the calking tool to be always held in the exact necessary relative position with the tube so as to render it impossible to disfigure either the boiler plate, or the bead being formed on the end of the tube.

3' indicates the ordinary offset on the tool to render the body 3, thereof, enough heavier

than the thin head 5 to avert all danger of undue trembling of the tool by reason of the action of the power impelling element on the shank 4.

What I claim as new and desire to secure is:

1. In combination with an ordinary tool for calking the ends of locomotive boiler tubes, a cylindrical body fitted to enter the end of the tube, and having a longitudinal slot therein, a slotted flange integral with said body and having an annular groove therein, semicircular in cross section, a ledge projecting over the back end of the groove, 15 a supporting plate pivotally and slidably mounted in the groove, springs for forcing said plate against the surface of the tool to

force its other edge against the inner surface of the tube.

2. In combination with an ordinary tool for calking the ends of tubes in locomotive boilers, a cylindrical body made to fit into the end of the tube and having a longitudinal slot in from one side, a ledge extending over one end of the slot, a plate adjustably secured in the slot, springs for forcing said plate outward, a flange integral with the body and having an annular groove adjacent to the body, and a handle adjustably mounted on the body and adapted to engage with, and support the tool.

Signed at Grand Rapids, Michigan, March 21, 1916.

JOHN F. BECK.
